UNITED STATES PATENT OFFICE.

PATRICK H. SPILLANE, OF WASHINGTON, DISTRICT OF COLUMBIA.

DESIGN FOR A SMOKER'S ASH TRAY.

Application filed March 18, 1921. Serial No. 453,403. Term of patent 14 years.

To all whom it may concern:

Be it known that I, PATRICK H. SPILLANE, a citizen of the United States, residing at Washington, in the District of Columbia, have invented a new, original, and ornamental Design for a Smoker's Ash Tray, of which the following is a specification, reference being made to the accompanying drawing, forming part thereof.

Fig. 1 of the drawing is a top plan of the smoker's ash tray.

Fig. 2 is a front elevation.

Fig. 3 is a rear elevation.

I claim:

The ornamental design for a smoker's ash tray, as shown.

PATRICK H. SPILLANE.
